CLAIM

The ornamental design for a bowl, as shown and described.

DESCRIPTION

FIG. 1 is a perspective view of a bowl showing our new design;

FIG. 2 is a top plan view of the bowl of FIG. 1;

FIG. 3 is a front elevational view of the bowl of FIG. 1; the rear elevational view of the bowl of FIG. 1 being the same; the left side elevational view of the bowl of FIG. 1 being the same; the right side elevational view of the bowl of FIG. 1 being the same; and,

FIG. 4 is a bottom plan view of the bowl of FIG. 1.

1 Claim, 2 Drawing Sheets
